JOSEPH CHUDNER, OF BROOKLYN, NEW YORK

ADJUSTABLE PRESSER FOOT GAUGE

Application filed April 13, 1931. Serial No. 529,836.

This invention has for its object the provision of an adjustable gauge in conjunction with a presser foot of a sewing machine, whereby means will be provided for guiding the work to obtain uniform hems of various widths and lines of stitching paralleling the edges of the hems, and also for gauging or indicating the widths of hems desired to be formed.

The nature of the invention and its distinguishing features and advantages will appear when the following specification is read in connection with the accompanying drawings, in which

Figure 1 is a perspective view of a presser foot selected to illustrate the gauge of the present invention shown applied thereto;

Figure 2 is a section on the line 2—2 of Fig. 1;

Figure 3 is a section on the line 3—3 of Fig. 2.

Referring now more particularly to the drawings, it will be apparent that there is shown a presser foot 10 having the usual needle slot, and a shank 11 for securing it in operative position on a sewing machine.

In accordance with the invention use is made of a work gauge 12 having an opening 13 therein which corresponds to the profile shape of the foot 10, to receive the latter therein, whereby the gauge 12 may be moved transversely in relation to the foot toward and away from the needle which operates up and down in the slot. An element 14 in the form of a screw is used, and it extends transversely through the shank 11, and also through a lug 15 extending rearwardly from the foot 10 on the side thereof opposite that having the shank 11, said element 14 being loose or, in other words, freely rotatable both in the shank 11 and lug 15. The element 14 has a manipulating knob 16 on one end which bears against the shank as at 17, and has a portion 18 which fits in a hole 19 in the shank. The element also has a head 20 on its other end which bears against the lug 15. The element 14 is thus mounted for rotation but is prevented from having axial movement. The gauge 12 has a nut or sleeve 21 secured there-

to, or formed integral therewith in threading engagement with the element 14.

From the foregoing it will be apparent that, by manipulating the knob to turn the screw element 14, the gauge element 12 may be moved toward or away from the needle according to the direction of rotation of the element 14, and that such element may therefore be adjusted in relation to the foot 10, and be held in the adjusted positions. In this way it is possible to guide the work passing beneath the foot 10 and also to gauge the width of a hem desired to be formed. If desired, the foot 10 may have a measuring scale 22 on the upper surface thereof. The lower edge portion of the gauge serves as a guiding means for the work, whereas, the upper edge portion thereof forms a means movable in relation to the scale 22 for indicating the various adjustments or widths.

Claim:

The combination with a presser foot, of a gauge provided with an opening to receive the foot therein, and means carried by the foot adjustably mounting said gauge in relation to the foot.

JOSEPH CHUDNER.
